UNITED STATES PATENT OFFICE.

MAX L. KAUFMANN, OF NEW YORK, N. Y.

DESIGN FOR A PIPE-FERRULE.

SPECIFICATION forming part of Design No. 26,324, dated November 24, 1896.

Application filed June 26, 1896. Serial No. 597,085. Term of patent 3¹ years.

To all whom it may concern:

Be it known that I, MAX L. KAUFMANN, residing at New York, in the county and State of New York, have invented and produced a new and original Design in a Combined Pipe-Ferrule, of which the following is a specification, reference being had to the accompanying drawings, wherein—

Figure 1 is a perspective view of the pipe-ferrule. Fig. 2 is a cross-section of the same. Fig. 3 is a transverse view of a modified form of ferrule embodying my design.

The leading feature of my design consists in a pipe-ferrule having one or more openings of considerable extent in the side walls thereof, through which suitable pictures or the like may be exposed.

In the drawings, A represents a pipe-ferrule which may be of any suitable configuration in cross-section. The side walls of this 20 ferrule are provided with one or more openings a, through which suitable pictures or the like c may be exposed, the said pictures being surrounded by a frame-like portion b, constituted of the body of the pipe-ferrule. 25

What I claim is—

The design for a pipe-ferrule substantially as shown and described.

MAX L. KAUFMANN.
